UNITED STATES PATENT OFFICE.

RALPH G. UTTER, OF FRIENDSHIP, NEW YORK.

HAY-TEDDER.

SPECIFICATION forming part of Letters Patent No. 372,344, dated November 1, 1887.

Application filed March 26, 1887. Serial No. 232,478. (No model.)

To all whom it may concern:

Be it known that I, RALPH G. UTTER, of Friendship, county of Allegany, and State of New York, have invented a certain new and 5 useful Improvement in Hay-Tedders, of which the following is a specification.

My invention relates to machines for tedding hay which are operated by horse-power.

I will describe in detail my improved hay- 10 tedder, and then point out the novel features in claims.

In the accompanying drawings, Figure 1 is a perspective front elevation of a hay-tedder embodying my improvement. Fig. 2 is a side 15 view of the same, a portion of the frame being removed to more clearly disclose certain parts. Figs. 3 and 4 are detail views. Fig. 5 is a perspective view showing certain parts of the machine, certain other parts being omitted which 20 might otherwise tend to obscure the parts illustrated.

Similar letters of reference designate corresponding parts in all the figures.

A A' designate the main wheels of the machine, mounted loosely upon an axle, B, journaled in suitable bearings in side pieces, B', of the main frame of the machine. These wheels act as drive-wheels for the machine. The hubs of these wheels are recessed upon 25 their outer sides to afford space for ratchet-wheels a, rigidly affixed to the ends of the axle B. Spring-actuated pawls b, pivoted upon the hubs at the rear of said recesses, are adapted to engage the ratchets a. When the machine is moving forward, the pawls operate to lock the axle B and the wheels A A' together, and they rotate together, thereby imparting motion to the tedding mechanism, as hereinafter to be more fully described. When the machine is 30 moving backward, the pawls play freely over the teeth of the ratchet-wheels, and no motion is imparted to the axle B.

Upon the axle B, adjacent to one of the wheels, (here shown as the wheel A,) is mounted a gear-wheel, C. This gear-wheel meshes with a pinion, D, keyed to one end of a shaft, D', journaled in suitable bearings in the side pieces, B', of the main frame. The pinion D is, as shown, outside the adjacent side piece, 45 B'. Inward of one of the side pieces, B', a

sprocket-wheel, E, is mounted upon the shaft D'. Motion transmitted to the pinion D causes the sprocket-wheel E to rotate in a reverse direction to the direction of the rotation of the wheels A A'. 55

The sprocket-wheel E imparts motion to another sprocket-wheel, H, mounted rigidly upon a shaft, H', near the extreme rear of the main frame. Motion is thus transmitted by means of a sprocket-chain, H², passing over the sprocket-wheels E and H. Upon the shaft H' are also rigidly mounted sprocket wheels H³.

Near the front of the machine are other sprocket-wheels, I, around which pass sprocket-chains F, also passing around the sprocket-wheels H³. Motion is thus imparted from the sprocket-wheels H³ to the sprocket-wheels I. The sprocket-wheels I are mounted upon studs extending from the sides of bars J, near the front ends of the latter. These bars are loosely 65 hung at their rear ends upon the shaft H inward of the sprocket-wheels H³. They are therefore free to be swung up and down upon the shaft H. 70

The sprocket-wheels I H³ transmit motion 75 to an endless carrier comprising a series of rakes, L. These rakes L consist of a series of fingers, l, which are affixed to bars l', extending between and secured to the chains F. Cross-slats L' also extend between the chains, 80 and are located intermediate of the rakes, whereby hay which may fall down from the rakes as the carrier travels upwardly will be caught and prevented from falling through. The fingers l are, as shown, coiled near the 85 ends, where they are secured to the bars l', in order that their resilience may be increased.

I have stated that the bars J may be swung up and down. I effect this, as here shown, by means of a lever, J², secured near one end to a rod, j, extending between the side portions 90 of the frame of the machine. Upon both sides this rod extends outside of the side portions of the frame, and is provided with crank-arms j³, which have a loose connection with 95 rods j⁴, which latter are in turn loosely connected at their lower ends with the journals of the wheels I. The upper portion of this lever extends into a position near the driver's seat J³ in such manner that it may be grasped 100

and moved by the driver to raise or lower the forward end of the carrier, as shown. The carrier is thus raised and lowered for the purpose of accommodating it to unevenness of ground or avoiding obstructions.

Of course, instead of using a lever to be operated by hand, one suitably arranged to be operated by foot might be used. In the construction shown a ratchet, β , is employed to secure the lever in different positions.

I prefer that the side frames of the machine shall be provided with screens P, by which the hay will be prevented from falling upon the gear-wheels outside the frame.

15 The sprocket-wheel E is adapted to be moved to and fro on the shaft D', in order that when desired said shaft may rotate freely without imparting motion to the sprocket wheel E, and thereby avoiding the transmission of motion 20 to the endless carrier. A convenient means for effecting this I have shown in Fig 4, which consists of providing said shaft for a short distance with a longitudinal feather or rib, and the hub of the sprocket-wheel E with a corresponding internal groove adapted to receive the feather or rib. When the feather or rib is within said groove, motion will of course be transmitted from the shaft to the sprocket-wheel; but when the sprocket-wheel is moved 30 into such a position that the feather or rib no longer engages the groove the shaft will rotate freely.

In this machine all parts are positively driven, and being few in number the machine is very cheap and easy of construction, while at the same time, owing to the construction and arrangement, it is not liable to get out of order.

I have filed an application for United States 40 Letters Patent for improvement in hay-tedders, Serial No. 208,925, July 24, 1886. In said application I show an axle, upon which driving-wheels are mounted, an endless carrier, sprocket-wheels for transmitting motion

to the endless carrier, gearing for transmitting motion from the axle to the sprocket-wheels, sprocket-chains comprised in the carrier, sprocket-wheels mounted upon stud-axes at the rear of the driving sprocket-wheels over which said chains pass, independently swinging bars, sprocket-wheels mounted in said swinging bars at or near the forward ends thereof, over which said chains also pass, and mechanism for imparting vertical movement to the swinging bars. In said application I 55 also show an endless carrier comprising chains and wheels over which said chains pass, certain of said wheels being mounted in swinging bars which are independent of each other, and levers whereby either of said bars may be 60 swung up or down independently of the other.

I do not herein lay claim to either of the foregoing arrangements and combinations of parts specifically.

What I claim as my invention, and desire to 55 secure by Letters Patent, is—

In a hay-tedder, the combination, with driving-wheels, of axles upon which said wheels are mounted, the gear-wheel C, shaft D', pinion D, mounted on the shaft D', the sprocket-wheel E, also mounted on the shaft D', the shaft H' to the rear of the shaft D', the sprocket-wheel H, mounted on the shaft H', the sprocket-chain H², passing round the sprocket-wheels E H, the sprocket-wheels H³, mounted on the 75 shaft H', the bars J, loosely hung upon the shaft H' at their rear ends, the sprocket-wheels I, mounted on the bars J at the forward ends of the latter, the sprocket-chains F, extending about the sprocket-wheels H³ and I, and mechanism, substantially such as described, for imparting vertical motion to the bars J, substantially as specified.

RALPH G. UTTER.
